Primary Examiner — Clint A Samuel(74) *Attorney, Agent, or Firm* — Timothy W. Menasco, Esq.; Harter Secrest & Emery LLP**CLAIM**

The ornamental design for a lighting device, as shown and described.

DESCRIPTION

FIG. 1 is a top perspective view of a lighting device in accordance with the present invention;

FIG. 2 is a front side view thereof, a rear side view being a mirror image thereof;

FIG. 3 is a right side view thereof, a left side view being a mirror image thereof;

FIG. 4 is a top view thereof;

FIG. 5 is a bottom view thereof; and,

FIG. 6 is a bottom perspective view thereof;

The lighting device is not limited to the scale shown herein. The broken lines of the Figures are for illustrative purposes only and form no part of the claimed design.
